UNITED STATES PATENT OFFICE.

FRANK S. LAND, OF KANSAS CITY, MISSOURI, ASSIGNOR TO THE GRAND COUNCIL OF THE ORDER OF DE MOLAY, OF KANSAS CITY, MISSOURI.

DESIGN FOR A BADGE OR SIMILAR ARTICLE OF JEWELRY.

Application filed May 24, 1926. Serial No. 17,818. Term of patent 14 years.

To all whom it may concern:

Be it known that I, FRANK S. LAND, a citizen of the United States, and a resident of the city of Kansas City, State of Missouri, have invented a new, original, and ornamental Design for Badge or Similar Article of Jewelry, of which the following is a specification, reference being had to the accompanying drawing, forming part thereof.

In said drawing Fig. 1 is a front view of a badge or similar article of jewelry embodying my invention, and Fig. 2 is an edge view thereof.

I claim:

The ornamental design for a badge or similar article of jewelry, as shown.

FRANK S. LAND.
